his Attorney.

UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA
RAILWAY BRAKING APPARATUS

RAILWAY BRAKING APPARATUS

Application filed June 20, 1928. Serial No. 287,006.

My invention relates to railway braking apparatus, and particularly to apparatus of the type comprising a braking bar located in the trackway and a motor for moving such bar into engagement with a part of a railway vehicle. More particularly my invention relates to means for controlling such motor device. railway braking apparatus, and another form of apparatus for accomplishing the same result is disclosed in an application for Letters Patent of the United States, Serial No. 187,525, filed April 29, 1927, by William C. McWhirter, for railway braking apparatus. The motor M is controlled by three magnet

I will describe one form of railway braking apparatus embodying my invention, and will then point out the novel features thereof in claims not set out in the following description.

The accompanying drawing is a view, partly diagrammatic, illustrating one form of railway braking apparatus embodying my invention.

Referring to the drawing, the reference characters 1 and 1^a designate the track rails of a stretch of railway track. Located on opposite sides of rail 1 and extending parallel therewith are two braking bars 2 and 3. Similar braking bars 2^a and 3^a extend parallel with rail 1^a on opposite sides thereof.

The braking bars 2, 3, 2^a and 3^a are operated by a fluid pressure motor designated in general by the reference character M. This motor, in the form here shown, comprises a cylinder 5 containing a reciprocable piston 6. The braking bars 2, 3, 2^a and 3^a are operatively connected with the piston 6 through a resilient linkage indicated diagrammatically on the drawing and including two springs 25 and 25^a and a lever 4 pivoted at point 4^a. When piston 6 occupies its left-hand position, the braking bars occupy their non-braking positions in which they are illustrated in the drawing. When piston 6 is moved to its right-hand position, however, the braking bars are moved inwardly toward the associated rails to their braking positions in which they engage the sides of the wheels of a railway vehicle traversing rails 1 and 1^a. The mechanical apparatus connecting the piston 6 with the braking bars forms no part of my present invention and is indicated diagrammatically for the sake of simplicity. One form of apparatus for operating trackway braking bars in the manner described is disclosed in Letters Patent of the United States, No. 1,626,919, issued May 3, 1927, to John P. Coleman, for

railway braking apparatus, and another form of apparatus for accomplishing the same result is disclosed in an application for Letters Patent of the United States, Serial No. 187,525, filed April 29, 1927, by William C. McWhirter, for railway braking apparatus. 55

The motor M is controlled by three magnet valves D, E and F. Valve F comprises a plunger 7 provided with an armature 7^a and a magnet 8. When magnet 8 is de-energized, plunger 7 occupies an upper position in which the right-hand end of cylinder 5 is connected with atmosphere through pipe 11 and port 10. When winding 8 is energized, however, plunger 7 is moved downwardly, disconnecting pipe 11 from port 10 and connecting this pipe through port 9 with a suitable source of fluid pressure not shown in the drawing. When magnet 8 of valve F is energized, therefore, the fluid pressure supplied to the right-hand end of cylinder 5 moves piston 6 to the left, thereby moving the braking bars to their non-braking positions. 70

Valve E is somewhat similar to valve F. When magnet 8 of the valve is de-energized so that plunger 7 occupies its upper position, the left-hand end of cylinder 5 is connected with atmosphere through pipe 12 and port 13. When magnet 8 of valve E is energized, however, plunger 7 is moved downwardly to blank pipe 12. 75 80

Referring now to valve D, when magnet 8 of this valve is de-energized, plunger 7 occupies an upper position in which it blanks pipe 12. When magnet 8 of valve D is energized, however, the plunger 7 is moved downwardly, thereby connecting pipe 12, through port 14, with a source of fluid pressure not shown in the drawing. It will be plain therefore that when valve E is closed and valve D is open, fluid pressure is supplied through pipe 12 to the left-hand end of cylinder 5. Piston 6 is then moved to the right, thereby moving the braking bars toward their braking positions. When valve D is closed and valve E is open, however, the left-hand end of cylinder 5 is connected with atmosphere.

Due to the resilient linkage interposed between the piston 6 and the braking bars, it is 100

obvious that the braking force exerted upon the vehicle depends upon the position of the piston 6, the braking force increasing as the piston moves to the right due to the greater deformation of the springs 25 and 25^a then caused by a vehicle occupying the rails 1 and 1^a.

The valves D and E are controlled in part by a circuit controller designated in general by the reference character H and comprising a movable plate operatively connected with the piston 6 and provided with two contact segments 26 and 28 separated by a member of insulation 27. The circuit controller H also comprises three fixed contacts 29, 30 and 31. When the piston 6 occupies its left-hand position, the contacts 29, 30 and 31 all engage the segment 26. When the piston 6 moves to the right, however, the segment 26 also moves to the right, and when the piston 6 reaches a position in which the braking bars controlled thereby engage the wheels of a vehicle, contact 29 moves into engagement with the insulation 27, thereby breaking contact 29-26. If the piston moves slightly beyond this position, the contact 29 engages segment 28. In similar manner, if the piston moves a small distance farther toward the right, contact 30 engages insulation 27 to break contact 30-26. Further movement of the piston to the right closes contact 30-28. Finally, when the piston 6 occupies a position almost at the end of its stroke to the right, contact 31 engages the insulation 27 to break contact 31-26. If the piston moves beyond this position, contact 31-28 is closed. It will be seen, therefore, that the positions of piston 6 in which the contacts 29, 30 and 31 separately engage the insulation 27 define positions of the braking bars which correspond to different braking forces applied to a vehicle.

The reference character K designates a fluid pressure responsive device which in the form here shown comprises a Bourdon tube 15 subjected to the pressure in pipe 17 communicating with the left-hand end of cylinder 5. The Bourdon tube 15 controls a contact 16 in such manner that the contact is closed only when the pressure in the left-hand end of the cylinder exceeds a predetermined low value.

The reference character G designates a manually operable selector comprising a lever 18 movable into engagement with any one of a plurality of fixed contacts 19, 20, 21, 22 or 23. The selector also comprises a fixed contact 24 so located that when lever 18 engages any of the contacts 20, 21, 22 or 23, the lever also engages contact 24.

As shown in the drawing, all contacts of selector G are open and all of the valves D, E and F are de-energized. Both ends of cylinder 5 are therefore connected to atmosphere and contact 16 of device K is open.

Piston 6 occupies its left-hand position so that contacts 29-26, 30-26 and 31-26 of circuit controller H are all closed, and the braking bars operated by piston 6 occupy their non-braking positions.

70

In explaining the operation of the apparatus, I will first assume that the operator in charge of the selector G wishes to cause a light brake application. He accomplishes this result by moving lever 18 into engagement with contact 20. Current then flows from terminal B of a suitable source of energy not shown in the drawing through contact 18-20 of selector G, wire 32 of contact 29-26 of circuit controller H, wires 33 and 34, and magnet 8 of valve D back to terminal C of the same source. At the same time, current flows from terminal B over contact 18-24 of selector G, wire 35, back contact 36 of a relay R which is now de-energized, wire 37, and magnet 8 of valve E to terminal C. Valve E is therefore closed to blank pipe 12, and valve D is open to admit fluid pressure to the left-hand end of cylinder 5. The pressure thus admitted to the cylinder closes contact 16 of device K and forces piston 6 to the right thereby driving the braking bars toward their braking positions. When the bars have reached a position in which they will engage the wheels of a vehicle, contact 29-26 of circuit controller H opens, thereby interrupting the circuit for magnet 8 of valve D and stopping the admission of fluid to the cylinder 5. Due to the inertia of the moving parts, the piston may stop in the position which it then occupies, and in this case the circuit for magnet 8 of valve E will remain closed. It will usually happen, however, that even if the valve D is closed, the expansion of the fluid already supplied to the cylinder 5 will cause a further movement of the piston toward the right sufficient to close contact 29-28. When this happens, current flows from terminal B over contact 18-20 of selector G, wire 32, contact 29-28 of circuit controller H, wire 38, contact 16 of device K, wire 39, winding of relay R to terminal C. Relay R then becomes energized to open its back contact 36. When this occurs, the circuit for magnet 8 of valve E opens, so that this valve exhausts fluid from the left-hand end of cylinder 5. The resulting pressure reduction continues until the pressure in the left-hand end of cylinder 5 is below the value required to hold contact 16 of device K closed. When this contact opens, relay R becomes de-energized, thereby reestablishing the circuit for magnet 8 of valve E and preventing further exhaust of the fluid from the cylinder. Under these conditions, then, the piston is held in position and the braking bars are maintained in positions where they will be engaged by a vehicle entering the retarder. The device K is adjusted, however, to a value such that the pressure behind the piston is so 130.

small that there will be little or no tendency to derail the vehicle as it engages the braking bars. If a vehicle now engages the braking bars, they are urged toward their non-braking positions. A portion of this movement of the bars may be taken up by the resilient link between the bars and the piston 6. A portion of the movement will be transmitted to the piston, however, moving this piston toward the left. As a result, contact 29-26 is again closed and pressure is admitted to the left-hand end of cylinder 5 by valve D, to return the piston to the position in which contact 29 engages the insulation 27. It will be seen, therefore, that the piston is maintained in the position defined by the contact 29 and when the piston is in this position a definite low braking force is exerted upon the wheels of a vehicle occupying the retarder.

If the operator wishes to cause a more severe brake application, he moves lever 18 into engagement with contact 21. With lever 18 in this position, contact 18-24 is still closed, so that the circuit for valve E is closed. The circuit for valve D, however, now passes from terminal B, over contact 18-21 of selector G, wire 40, contact 30-26, wires 33 and 34, magnet 8 of valve D to terminal C. Valve D therefore opens to admit fluid to cylinder 5 and the piston is moved to the right until contact 30 engages the insulation 27, whereupon the circuit for magnet 8 is interrupted and valve D is closed. If the expansion of the fluid in the cylinder moves the piston to a position into which contact 30-28 is closed, relay R becomes energized to open the valve E. As a result, the pressure in the left-hand end of cylinder 5 is reduced to the low value at which the device K operates. When the vehicle enters the retarder, under these conditions, the braking bars are moved back by the wheels of the vehicle against the comparatively low pressure then existing in the left-hand end of cylinder 5. This movement of the piston 6, however, closes contact 30-26, whereupon valve D opens to admit fluid to the cylinder and restore the piston to the position in which contact 30 engages insulation 27. It follows, therefore, that when contact 18-21 of selector G is closed, the piston 6 is held in a position in which contact 30 engages insulation 27 and with the parts in this position a greater braking force is obtained than when the piston occupies the position defined by contact 29.

In similar manner when contact 18-22 of selector G is closed, the valves which control the fluid pressure in the left-hand end of cylinder 5 are controlled by contacts 31-26 and 31-28 of circuit controller H. It follows that when contact 18-22 is closed, the piston 6 is held in a position in which contact 31 engages insulation 27. Finally, when lever 18 is moved into engagement with

magnet 8 of valve D over a circuit which passes from terminal B over contact 18-23 of selector G, wires 42 and 34, and magnet 8 of valve D to terminal C. When this circuit is closed, valve D is held open independently of the position of the piston 6. Under these conditions, the braking bars are held in their full braking positions by the full pressure applied to port 14.

It will be seen, therefore, that the circuit controller H, operated by the piston, permits a plurality of braking pressures to be obtained by controlling the admission of pressure to the cylinder in accordance with the position of the piston. One advantage of this feature is that when a vehicle enters the retarder, the braking bars are forced away from their braking positions by the first truck of the vehicle which enters the retarder. The

valve D is then opened to supply to cylinder 5 fluid at sufficient pressure to restore the piston to the position corresponding to the position of selector G. When the next truck of the vehicle enters the retarder, the piston will again be forced back and additional fluid will be admitted to the cylinder to maintain the piston in its selected position. It will be seen therefore that the unit pressure on each wheel of the vehicle is maintained substantially constant, the total pressure on the wheels of the vehicle increasing as additional wheels enter the retarder. In similar manner, as the vehicle leaves the retarder, the pressure in the cylinder will be successively decreased by the corresponding movement of the piston upon the departure of each successive truck from the retarder.

It should also be pointed out that if the selector G is moved from a position corresponding to a high braking force to a position corresponding to a lower braking force, the control of the pressure through the cylinder follows this movement of the selector directly. Thus, if the selector is in a position in which contact 18-22 is closed so that the piston is held in a position in which contact 31 engages the insulation 27, and the operator wishes to reduce the braking pressure to the value corresponding to contact 18-20 of the selector, he may do so by simply moving the selector to close contact 18-20. The control circuit for valve D is then shifted to contact 29-26 of circuit controller H but contact 29 now engages segment 28 and the relay R therefore becomes energized to open valve E and exhaust fluid from the cylinder 5. If the wheels of a vehicle are engaging the braking bars these bars will be forced back to open contact 29-28 when the pressure has been sufficiently reduced. The piston 6 will thereafter be held in the position defined by contact 29. It follows, therefore, that the response of the braking appa-

ratus to changes in the position of selector G, and means effective if the piston is moved past such position in the other direction to increase the pressure in said cylinder.

If the operator wishes to restore the braking bars to their non-braking positions, he moves lever 18 to the position in which it is illustrated in the drawing, thereby opening all contacts of the selector. As a result, valve D is closed and valve E opens to exhaust the left-hand end of cylinder 5. The operator then closes contact 18-19, whereupon, current flows from terminal B, through contact 18-19 of selector G, wire 47, and magnet 8 of valve E to terminal C. Plunger 7 of valve F therefore moves downwardly, and fluid pressure is admitted to the right-hand end of cylinder 5. Piston 6 then moves to the left and drives the braking bars to their non-braking positions. The lever 18 may then be restored to the position in which it is illustrated in the drawing, wherein the circuits for all of the valves D, E and F are open.

Although I have herein shown and described only one form of railway braking apparatus embodying my invention, it is understood that various changes and modifications may be made therein within the scope of the appended claims, without departing from the spirit and scope of my invention.

Having thus described my invention, what I claim is:

1. Railway braking apparatus comprising a braking bar located in the trackway, a fluid pressure motor for operating said bar, a circuit controller responsive to the condition of said motor, a manually operable selector, a first magnet for controlling the admission of fluid to said motor, a circuit for said first magnet controlled by said selector and by said circuit controller, a second magnet for controlling the exhaust of fluid from said motor, and a circuit for said second magnet controlled by said selector and by said circuit controller.

2. Railway braking apparatus comprising a braking bar located in the trackway, a fluid pressure motor for operating said bar, a circuit controller responsive to the condition of said motor, a manually operable selector, means controlled by said selector for admitting fluid to said motor, a contact responsive to the pressure in said motor, and means controlled by said contact and by said circuit controller for exhausting fluid from said motor.

3. Railway braking apparatus comprising a braking bar located in the trackway, a cylinder, a piston reciprocable in said cylinder and operatively connected with said bar, manually controlled means for at times admitting fluid to said cylinder to move the piston in one direction to a predetermined position in its stroke, means effective if the piston moves past such position in said direction to reduce the pressure in said cylinder,

4. Railway braking apparatus comprising a braking bar located in the trackway, a cylinder, a piston reciprocable in said cylinder and operatively connected with said bar, manually controlled means for at times admitting fluid to said cylinder to move the piston in one direction, means for interrupting the admission of fluid to the cylinder when the piston reaches a predetermined position in its stroke, and means effective if the piston is moved in the opposite direction past said position to admit fluid to the cylinder to return the piston to said position.

5. Railway braking apparatus comprising a braking bar located in the trackway, a cylinder, a piston reciprocable in said cylinder and operatively connected with said bar, means for at times admitting fluid to said cylinder, a circuit controller responsive to the position of said piston, and means controlled by said circuit controller for at times exhausting fluid from said motor.

6. Railway braking apparatus comprising a braking bar located in the trackway, a cylinder, a piston reciprocable in said cylinder and operatively connected with said bar, means for at times admitting fluid to said cylinder, a circuit controller responsive to the position of said piston, a contact responsive to the pressure in said cylinder, and means controlled by said circuit controller and by said contact for at times exhausting fluid from said motor.

7. Railway braking apparatus comprising a braking bar located in the trackway, a cylinder, a piston reciprocable in said cylinder and operatively connected with said bar, a circuit controller comprising a plurality of contacts operated successively as the piston moves through its stroke, a magnet for controlling the admission of fluid to said cylinder, and means for controlling said magnet over a selected one of said contacts.

8. Railway braking apparatus comprising a braking bar located in the trackway, a cylinder, a piston reciprocable in said cylinder and operatively connected with said bar, means for at times admitting fluid to said cylinder, a plurality of contacts operated successively as the piston moves through its stroke, a magnet for controlling the exhaust of fluid from said cylinder, and means for controlling said magnet over a selected one of said contacts.

9. Railway braking apparatus comprising a braking bar located in the trackway, a cylinder, a piston reciprocable in said cylinder and operatively connected with said bar, means for at times admitting fluid to said cylinder, a plurality of contacts operated successively as the piston moves through its stroke, a device responsive to the pressure in

- said cylinder, a magnet for controlling the exhaust of fluid from said cylinder, and means controlled by said device and by a selected one of said contacts for controlling said magnet.
- 5 10. Railway braking apparatus comprising a braking bar located in the trackway, a cylinder, a piston reciprocable in the cylinder, resilient linkage connecting said bar with said piston, means for at times admitting fluid to said cylinder to move said piston in one direction, means operating when the piston reaches a certain position in its stroke to interrupt the admission of fluid to the cylinder, means effective if the piston moves past such position in said one direction to reduce the pressure in said cylinder to a low value, and means operating when the piston is moved past such position to supply fluid to the cylinder to return the piston to said position.
- 10 15 20 25 30 35 40 45 50 55 60 65 70 75 80 85 90 95 100 105 110 115 120 125 130
11. Railway braking apparatus comprising a braking bar located in the trackway, a cylinder, a piston reciprocable in the cylinder, resilient linkage connecting said bar with said piston, a manually operable selector, a manually controlled selector, means for at times admitting fluid to said cylinder to move the piston in one direction, means operating when the piston reaches a selected position in its stroke which depends upon the condition of said selector to interrupt the admission of fluid to said cylinder, means effective if the piston moves past such position in said one direction to reduce the pressure in said cylinder to a low value, and means operating when the piston is moved past such position in the other direction to supply fluid to the cylinder to return the piston to said position.
12. Railway braking apparatus comprising a braking bar located in the trackway, a fluid pressure motor for operating said bar, and means for controlling the admission of fluid to said motor in accordance with the position of a movable part of said motor.
13. Railway braking apparatus comprising a braking bar located in the trackway, a fluid pressure motor for operating said bar, a circuit controller responsive to the position of a movable part of said motor, and means controlled by said circuit controller for governing the admission of fluid to said motor.
14. Railway braking apparatus comprising a braking bar located in the trackway, a fluid pressure motor for operating said bar, a circuit controller responsive to the position of a movable part of said motor, a manually operable selector, and means controlled by said selector and by said circuit controller for governing the admission of fluid to said motor.
15. Railway braking apparatus comprising a braking bar located in the trackway, a fluid pressure motor for operating said bar,
